28 Claims. (Cl. 214—8.5)

1

This invention relates to packaging machines for feeding pharmaceutical applicator pads, etc., to metal foil or other pliable wrappers in which they are subsequently sealed, and it has for its object to provide a novel and improved method and apparatus for this purpose.

Another object of the invention is to provide a simple and efficient method and apparatus for automatically removing predetermined quantities of stacked articles, such as pharmaceutical applicator pads, from a supply source and conveying them to a packaging point.

Another object is to convey predetermined quantities of stacked articles of the above type from a supply source and deposit them on continuous strips of wrapping material in uniform equally spaced files suitable for subsequent sealing and severing into separate packages.

Still another object is to provide a novel combination of a supply magazine containing a stack of articles to be wrapped, and a movable carrier having suction means for periodically removing specific quantities of articles from the magazine and conveying them to the wrapping point without dislodging other articles in the magazine.

A further object is to provide a machine of the type specified in which porous air-pervious articles such as fabric applicator pads are stacked in predetermined groups interleaved with relatively impervious spacers throughout the depth of the magazine, whereby suction fingers on the movable carrier in skirting the magazine will always attract and detach only one group of pervious pads and its underlying impervious spacer.

Another object is to provide additional suction means for stripping the impervious spacer from each moving suction finger after it leaves the magazine and before it reaches the point where it deposits its cluster of applicator pads on the wrapping material.

A still further object is to provide a machine of the foregoing type having novel and improved details of construction and features of operation.

Various other objects and advantages will appear as the nature of the invention is more fully disclosed.

The machine disclosed herein for purposes of illustration is intended primarily for use in packaging pharmaceutical applicator pads or discs in sanitary wrappers which are usually made of laminated metal foil or other pliable material, although it will be evident as the description proceeds that the invention may also be used to advantage in many other situations.

The articles which we have chosen to illustrate the invention are porous fabric pads or

2

discs which serve as vehicles for an eye lotion for the relief of local eye irritations. Of course, it would be possible to pack quantities of these damp medicated applicator pads in glass jars or the like for use in hospitals or infirmaries, but the average user requires only a couple of pads to relieve his tired eyes and we therefore usually pack a pair of pads in a sealed foil wrapper which may be carried in the pocket or purse and can easily be ripped open and discarded on the spot.

For use in this particular situation the machine of the present invention has one or more magazines in which the dry porous pads are stacked in such a way that each pair of pads is separated from each succeeding pair of pads by a non-porous spacer made of paper or other suitable material which is substantially impervious to the passage of air. The machine includes a movable carrier having a plurality of suction fingers which move over the open-ended magazines and attract the topmost pair of porous pads and their underlying spacer, but cannot unseat the next succeeding pads beneath the substantially air-impervious spacer. The contents of the magazines are constantly raised by an elevator mechanism, and every time a suction finger sweeps over a magazine it seizes a stack of two pads and their underlying spacer and carries them toward the point where they are to be deposited on moving strips of wrapping foil.

Before the loaded suction fingers reach the wrapping station, however, they pass over a battery of suction nozzles which act only on the impervious spacers which are thereby stripped off and discarded as the suction fingers continue to transport the pads, now unencumbered by the spacers, to their final destination. Various novel means are employed to insure the proper timing and functioning of the magazine feed, the suction pick-up, the stripping off and discarding of the spacers, and the positioning of the pads on the strips of wrapping material, all as hereinafter described in detail.

Although the novel features which are characteristic of this invention are set forth more in detail in the claims appended hereto, the nature and scope of the invention may be better understood by referring to the following description, taken in connection with the accompanying drawings forming a part thereof, in which a specific embodiment has been set forth for purposes of illustration.

In the drawings:

Fig. 1 is a plan view of a machine embodying the invention;

Fig. 2 is a horizontal section on line 2—2 of Fig. 4, through the pad-supply magazine;

Fig. 3 is a horizontal section on line 3—3 of Fig. 4, showing the drive for actuating the magazine elevator, and the bottom support for the magazine;

Fig. 4 is an enlarged front elevation of the machine, looking in the direction of the arrow *a* in Fig. 1, with parts broken away to simplify the showing;

Fig. 5 is an enlarged horizontal section on line 5—5 of Fig. 4, showing details of the air control cams and associated mechanisms;

Fig. 6 is a horizontal section on line 6—6 of Fig. 13, showing the cam mechanism for controlling the suction nozzles of Fig. 13;

Fig. 7 is a detail view showing one of the suction fingers on the rotatable carriage as it picks up a pair of pervious pads and an impervious spacer from the supply magazine;

Fig. 8 is a detail view showing the same suction finger as it carries said pads and spacer over one of the stationary suction nozzles of Fig. 13 to dislodge and discard the spacer;

Fig. 9 is a vertical section on line 9—9 of Fig. 10, showing the mechanisms for actuating the air control valves of the rotatable suction fingers;

Fig. 10 is a horizontal section taken on line 10—10 of Fig. 9;

Fig. 11 is a horizontal section taken on line 11—11 of Fig. 9;

Fig. 12 is a detail of the valve resetting device, looking in the direction of the arrow *b* in Fig. 11;

Fig. 13 is an elevation of the stationary suction nozzles and associated control mechanisms (shown in plan in Fig. 6) for dislodging and discarding the spacers in the manner illustrated in Fig. 8;

Fig. 14 is a broken vertical section on line 14—14 of Fig. 4, showing the mechanisms for elevating the platform which supports the stacks of pads and spacers in the supply magazine;

Fig. 15 is a top plan view of the supply magazine, showing same detached from the frame of the machine;

Fig. 16 is a vertical section taken on line 16—16 of Fig. 15;

Fig. 17 is a vertical section on line 17—17 of Fig. 18, showing the guides for positioning the pads as they are deposited on the travelling strips of wrapping material;

Fig. 18 is a horizontal section taken on line 18—18 of Fig. 17; and

Fig. 19 is a transverse section taken on line 19—19 of Fig. 18.

In the following description certain specific terms are used for convenience in referring to the various details of the invention. These terms, however, are to be interpreted as broadly as the state of the art will permit.

The machine shown herein for purposes of illustration includes a flat horizontal table 1 mounted on suitable standards 2, as shown in Figs. 1 and 17.

A plurality of continuous strips of wrapping material 3 (here shown to be three in number) are strung in spaced parallel relation on the table 1, and suitable means (not shown) are provided for moving the strips 3 intermittently in a longitudinal direction as indicated by the arrows in Fig. 1.

The strips of wrapping material 3 may be of any type or construction suitable for packaging

moist pharmaceutical products. For example, we have used a laminated strip comprising an outer layer of metal foil, an intermediate layer of glassine paper secured thereto by a water-soluble adhesive, and a final layer of metal foil secured to said paper by a thermoplastic waterproof coating, the last-mentioned layer of foil having its outer surface coated with a vinyl-type thermoplastic lacquer permitting two such strips of wrapping material to be joined together upon the application of heat and pressure.

In practice, the continuous wrapping strips 3 are preferably unwound from reels (not shown) which may be mounted at the left of the machine as viewed in Fig. 1; and, as the strips 3 move intermittently along the table 1 in the direction of the arrows in Fig. 1, the mechanisms of the present invention deposit the applicator pads 4 upon the wrapping strips at uniformly spaced intervals as indicated in Figs. 1 and 5.

In describing the present invention, it will be assumed for purposes of illustration that the pads 4 are porous fabric applicators to be impregnated with a suitable medicament or lotion for application to the eyes for the relief of local irritations, and that therefore two such pads 4 are to be packed, one on top of the other, in each wrapper. The purpose of the present invention is to automatically remove the pads 4 in stacks of two (or any other predetermined number) from a magazine and deposit said stacks of pads on the intermittently moving wrapping strips 3 in uniform files as shown in Fig. 1. Once this had been done, the subsequent depositing of a few drops of eye lotion on each stack of pads 4, and the final sealing of the medicated pads in their wrappers, form no part of the present invention and therefore will not be described in detail. However, it may be mentioned that any suitable means may be employed to cover the medicated pads 4 on each wrapping strip 3 with another similar wrapping strip, then heat-seal the two superimposed wrapping strips together along their longitudinal edges as well as transversely between each stack of pads 4, and then sever the individually sealed wrappers (each containing a "sandwich" of two medicated pads 4) from the continuous sealed strips. Or, if desired, the product may be marketed in the form of elongated sausage-like strips folded accordion-wise in a box, with each stack of medicated pads sealed off from the adjacent stacks in the chain, thus permitting the user to tear off and use the contents of one compartment without exposing the adjacent one.

In the following description of the invention, we shall first describe the construction and operation of the magazine which supplies the pads 4 to be deposited on the wrapping strips 3.

Magazine

The supply magazine, represented generally by the reference numeral 6 in Figs. 1, 2, 4, 5, 14 and 15, is detachably secured to the machine and may be readily removed for replacement and refilling.

The upright magazine 6 comprises horizontal top and bottom plates 7 and 8, respectively, secured together by vertical side walls 9 and 10 and by a pair of vertical rods 12 which are secured to the top and bottom plates by nuts 13. Another pair of vertical rods 14 are secured between the top and bottom plates 7 and 8 and have their extremities reduced in diameter and projected outwardly through holes in said plates 7 and 8 to form pins 14a and 14b which serve to secure

the magazine to the frame of the machine as hereinafter more fully described.

The magazine 6 contains three vertical supply tubes or compartments 15 which are secured to the top and bottom plates 7 and 8 and are open at the top to permit the applicator pads 4 to be inserted therein when loading the magazine, as well as to permit said pads to be withdrawn through said open tops during the operation of the machine, as hereinafter described. In actual practice the supply tubes 15 are also open at the bottom because there is no necessity for closing the bottoms of said tubes, as will presently appear. The outer or front faces of the tubes 15 (as viewed in Figs. 1, 2, 4 and 5) have elongated vertical openings or slots 16 which are wide enough to permit the insertion of the operator's fingers when stacking the pads 4 in the tubes. The inner or rear faces of the tubes 15 (as viewed in Figs. 1, 2, 4 and 5) have elongated vertical slots 17 which are diametrically opposite the slots 16 but are of less width, since the slots 17 need only be wide enough to admit the stems of the vertically movable platforms which support and elevate the stacks of pads 4 within the tubes 15, as will now be described.

The magazine tubes 15 each contain a circular horizontal elevator platform 19 of a diameter slightly smaller than the internal diameter of the tube itself, as best shown in Figs. 2 and 14. The platforms 19 have axially depending lugs 20 mounted on horizontal stems 21 which extend outwardly through the narrow vertical slots 17 at the rear of the tubes 15 and are secured by screws 22 to a vertically movable cross-bar 23, as shown in Fig. 2. The cross-bar 23 has two spaced vertical holes 24 through which pass the stationary vertical rods 14 of the magazine 6, as also shown in Fig. 2. It will thus be evident that when the cross-bar 23 is moved vertically up or down on the rods 14, it will carry the elevator platforms 19 up or down in their respective magazine tubes 15.

As shown in Figs. 2 and 14, the inner central portion of the vertically movable cross-bar 23 has a rectangular channel 25 containing a rectangular block 26 supported by a headed pin or bolt 28 which extends freely through a hole 29 in the cross-bar 23. A coil spring 30 surrounds the bolt 28 and is compressed between the block 26 and the inner face of cross-bar 23, so that the spring 30 constantly urges the block 26 in an outward direction in channel 25, or toward the left as viewed in Fig. 14. The outer face of the block 26 (the face to the top of Fig. 2, or to the left in Fig. 14) has a semi-circular threaded groove 31 which is adapted to mesh with a vertical threaded shaft 32 on the frame of the machine for the purpose of actuating the block 26, cross-bar 23 and elevator platforms 19.

The vertical threaded shaft 32 is journaled in the top and bottom plates 34 and 35 of a channel-shaped support 36 which is welded or otherwise secured to the angular struts 37 constituting part of the framework of the machine. The lower end of shaft 32 extends downwardly through the bottom plate 35 and carries a bevel gear 38 meshing with a companion gear 39 on a shaft 40 which is journaled in bearings 41 secured to the base of the machine, as shown in Figs. 3, 4 and 14. The shaft 40 carries another bevel gear 43 meshing with bevel gear 44 on vertical shaft 45 which is journaled in bearing brackets 46 on the frame of the machine, as shown in Figs. 3 and 4. The shaft 45 in turn carries a bevel gear 47 meshing

with bevel gear 48 on the main drive shaft 49 of the machine. The main drive shaft 49 rotates continuously when the machine is in operation; hence the vertical threaded shaft 32 rotates continuously during the operation of the machine, and the rotation of said shaft 32 is always in a direction to elevate the threaded block 26 (and the elevator platforms 19) when said block 26 is in mesh with the shaft 32, as will now be described.

During the operation of the machine the magazine chambers or tubes 15 will eventually be emptied, and it is therefore necessary that the magazine 6 be quickly removable as a unit in order to refill it, or else replace it with a duplicate loaded magazine. In order to permit the magazine 6 to be quickly secured to, and detached from the machine, the bottom side walls of the stationary channel-shaped support 36 contain pivot pins 50 (Fig. 3) on which are journaled a pair of ears 51 carried by a bracket 52, as best shown in Figs. 3, 4 and 14. A pair of headed bolts 54 extend freely through slightly enlarged holes 55 in the bracket 52 and are threaded into the bottom plate 35 of the channel-shaped support 36, as shown in Figs. 3 and 14. Coil springs 56 are compressed between the heads of bolts 54 and the depending face of bracket 52. The expanding force of springs 56 thus tends to hold the bracket 52 in contact with the bottom plate 35 of the channel-shaped support 36 as shown in Fig. 14, while at the same time permitting said bracket 52 to be tipped or canted in a clockwise direction as viewed in Fig. 14 against the force of springs 56. The horizontal face of bracket 52 contains two spaced holes 57 (Figs. 3 and 14) which are adapted to receive the depending pins 14b on the lower ends of the vertical rods 14 of magazine 6 for the purpose of locking the lower end of magazine 6 on the bracket 52.

For the purpose of locking the upper end of magazine 6 to the frame of the machine, it will be recalled that the pins 14a (constituting the upper ends of the two vertical rods 14 of the magazine) project outwardly through holes in the top plate 7 of the magazine, as shown in Figs. 14 and 15. These pins 14a fit into slots 58 in a stationary bar 59 which is secured by screws 60 to the top plate 34 of the channel-shaped support 36 on the frame of the machine. When the pins 14a are thus seated in slots 58 they are locked therein by a sliding latch 62 which is secured by a slot-and-pin connection 63 to bar 59 and his lips 64 which straddle the pins 14a and thus secure them (and the upper end of magazine 6) to the bar 59 as shown in Fig. 14. The latch 62 is normally held in its locked position by a spring 65 secured to a pin 66 on the latch and to the channel-shaped support 36 on the frame of the machine, as shown in Fig. 15.

When the magazine 6 is locked on the frame of the machine as shown in Fig. 14, the semi-circular threaded groove 31 in block 26 of the magazine elevator unit will mesh with the threads 65 of the vertical threaded shaft 32 on the frame of the machine, and rotation of said shaft 32 will raise the cross-bar 23 and the elevator platforms 19 as previously mentioned. When it is desired to remove the magazine 6 from the machine for refilling or replacement, the operator simply moves the latch 62 toward the left in Fig. 15 against the tension of spring 65, thus withdrawing the locking lips 64 from the slots 58 and from engagement with pins 14a, and permitting the magazine to be tilted outwardly as shown in Fig.

15. In thus tilting the magazine, the bracket 52 supporting the bottom of magazine 6 at the base of the machine (Fig. 14) will tilt slightly on its pivot pins 50 (in a clockwise direction as viewed in Fig. 14) enabling the pins 14b on the bottom of the magazine to be withdrawn from the holes 57 in bracket 52 and permitting the magazine 6 to be lifted bodily from the machine.

By referring to Figs. 1, 4, 5, 14 and 15 it will be noted that a narrow horizontal bar 68 extends lengthwise across the magazine 6 in alignment with the top plate 7 and is detachably secured to the upper ends of the magazine walls 9 and 10 by wing nuts 69. The bar 68 carries three flexible spring fingers 70 which are secured thereto by screws 71, and these fingers 70 project inwardly a short distance and overlie the respective elevator platforms 19 in the supply tubes 15 in alignment with the slots 16 in said tubes. As the elevator platforms 19 rise in the magazine tubes 15 during the operation of the machine, thereby elevating the stacks of pads 4 which are stacked on said platforms 19, the flexible fingers 70 press lightly upon the topmost pad 4 in each tube 15 at a point adjacent the peripheral edge of each such topmost pad, as illustrated in Figs. 1, 4, 5, 7 and 15. As a result, these flexible fingers 70 exert a light compressing or compacting force upon the rising columns of pads 4 in the magazine compartments or tubes 15; and this light compressive force of the fingers 70 also tends to slightly tilt up the edges of the pads 4 which are diametrically opposite the fingers 70 so that these forward or tipped-up surfaces of the pads 4 are more readily seized by the rotating suction fingers which are now about to be described.

Suction pick-up

In describing the suction pick-up whereby the so-called pads 4 in magazine tubes 15 are removed from said tubes and deposited on the continuous wrapping strips 3 of Fig. 1, it is desired to emphasize the fact that the invention is not limited to the handling of any particular shape, size, number or composition of the articles which we refer to as "applicator pads" merely for purposes of illustration. The machine described herein for the purpose of illustrating the invention is intended primarily for packaging pervious fabric pads 4 which serve as combined vehicles and applicators for a medicament, preferably an eye lotion. For this reason we desire each sealed foil wrapper to contain a "stack" of two superimposed applicator pads 4, one for each eye.

Accordingly, the supply tubes 15 of the magazine 6 used with this particular machine are stacked with each pair of applicator pads 4 separated from each succeeding pair of pads 4 by a similarly shaped spacer 72 of specially treated paper or other suitable material which is relatively impervious to the passage of air therethrough. Thus, by referring to Fig. 7 it will be observed that the two topmost "discs" in the magazine tube 15 are porous, relatively air-pervious fabric applicator pads 4, while the third "disc" from the top of the stack is a relatively air-impermeable spacer 72. Immediately beneath said spacer 72 are two more applicator pads 4 followed by another spacer 72, and so on to the bottom of the stack. When air suction is applied to the topmost pad 4 in Fig. 7, in a manner presently to be described, such suction will readily penetrate both the topmost pad 4 and the next pad 4 directly beneath, and it will exert a lifting force on these two top pads 4 as well as on the

third "disc" which is a spacer 72. However, this air suction will not permeate the relatively impermeable spacer 72, at least not sufficiently to exert a lifting action on the pads beneath said spacer.

The suction pick-up mechanism for performing the above mentioned operation comprises a rotary carriage which is generally designated by the reference numeral 75 in Figs. 1, 4 and 9.

10 As previously described, the vertical shaft 45 of the machine is rotated continuously, through bevel gears 47 and 48, by the main drive shaft 49 (Fig. 4). This vertical shaft 45 extends upwardly through a stationary cylindrical guard 76 and bracket 77 secured by bolts 78 to the frame of the machine, and it is journaled in bearings 79 in the upper end of said guard 76 as shown in Fig. 9. The upper end of shaft 45 is keyed at 80 to a block 81, and a hood 82 is keyed at 83 to said block 81 as shown in Fig. 9. Accordingly, it will be seen that block 81 and hood 82 rotate with the shaft 45.

25 The rotary block 81 carries three suction pipes 85 which are equally spaced and extend outwardly like the spokes of a wheel, as best shown in Figs. 1 and 4. The inner ends of pipes 85 communicate within the block 81 with a central tube 86 which is connected by a suitable coupling 87 to a suction hose 88, as shown in Figs. 4 and 9. 30 Throughout the operation of the machine air suction is applied to the hose 88 in any suitable manner, as well as to the tube 86 and the suction pipes 85. The outer ends of suction pipes 85 are turned downwardly in a vertical direction 35 and carry individual valve blocks 89 as shown in Figs. 4 and 9, each pipe 85 having its own valve block 89 as will be apparent from Fig. 1. Suitable braces 90 connect the valve blocks 89 to each other and to the hood 82 for the purpose of strengthening the assembly, as shown in Fig. 1.

40 The valve blocks 89 (which are all identical) each have a depending pipe 91 carrying a horizontal suction pipe or arm 92, each of which arms 92 extends outwardly in the same vertical plane as its own associated suction pipe 85, as shown in Figs. 1 and 4. Each of the suction arms 92 carries three vertically depending suction fingers 94 which are equally spaced from each other by a distance such that each of the three fingers 94 will pass directly over one of the three magazine tubes 15 during the operation of the machine. Furthermore, the suction fingers 94 are of such length that they will just clear the tops of the respective magazine tubes 15 (Fig. 4) and thus enable the suction in said fingers 94 to act on, and readily attract, the contents of said tubes 15 as indicated in Fig. 7.

45 Each valve block 89 contains a horizontally movable valve stem 95 the hollow interior of 50 which contains valve ports 96 (Fig. 9) and the outer end of which carries a block 97 containing a roller 98 which is forced outwardly (toward the right in Figs. 4 and 9) by a coil spring 99 compressed between the valve block 89 and the 55 roller block 97. Whenever a coil spring 99 moves its valve stem 95 outwardly (toward the right in Fig. 9) the interior valve ports 96 of that valve stem are in the open position (as is the case in Fig. 9) and the suction constantly applied to tube 86 (top of Fig. 9) draws air upwardly through all three suction fingers 94, suction arm 92, pipe 91 of that particular valve block 89 (Fig. 4) valve ports 96 and suction pipe 85 which is connected to the tube 86 (Fig. 9). It will be noted 60 from Fig. 9 that the air which is thus drawn up

through pipe 91 takes a somewhat circuitous course in passing between the two interior valve ports 96 in stem 95 due to the fact that the two valve ports 96 are not directly aligned with each other. This prevents the air from rushing directly in a straight line from pipe 91 through suction pipe 85 the instant the valve ports 96 are opened, and makes for smoother operation of the suction pick-up.

However, whenever any one of the valve stems 95 is forced inwardly (toward the left in Figs. 4 and 9) against the pressure of its coil spring 99, the interior valve ports 96 of that valve stem will be moved to the closed position, thus cutting off the suction in the pipe 91 of that particular valve block, and, of course, cutting off the suction in the suction arm 92 and the three suction fingers 94 associated with that particular valve block. We shall now describe the means acting on the rollers 98 on blocks 97 to control the outward and inward movement of the valve stems 95 which carry said blocks 97 and rollers 98.

The upper end of stationary guard 76 (which surrounds the rotatable vertical shaft 45 in Figs. 4 and 9) carries a collar 100 which is secured thereto by set screws 101 (Fig. 9). The upper face of this collar 100 carries a stationary discontinuous ring 102 which is secured to said collar by screws 103 (Figs. 5, 9 and 10). The broken or discontinuous ring 102, as its name implies, is an annular ring which is less than 360° in circumference. Its precise shape is shown in Fig. 5; and it is also shown in Fig. 10 where it is not only labeled with the reference numeral 102 but is also shaded with horizontal cross-hatched lines to distinguish it from the other elements in Fig. 10. The outer peripheral edge of the stationary broken ring 102 is in the path of travel of the rollers 98 on the blocks 97 of the three valve stems 95 which, of course, rotate continuously with the entire rotary carriage 75 during the operation of the machine.

Whenever the roller 98 of any valve stem 95 engages and rides upon the peripheral edge of the stationary broken ring 102 that valve stem 95 is held in closed position (closing its valve ports 96) against the force of its coil spring 99, and whenever this condition prevails no suction will be applied to the suction arm 92 or suction fingers 94 of that particular valve block 89. However, whenever the roller 98 of any valve stem 95 rides off the peripheral edge of the stationary broken ring 102 (as it must do whenever it reaches the terminus of said ring 102) the force of coil spring 99 will instantly force that valve stem outwardly (toward the right in Figs. 4 and 9) thereby opening the valve ports 96 and applying suction to the suction arm 92 and suction fingers 94 of that particular valve block 89.

The rotary carriage 75 rotates continuously in a clockwise direction as viewed in Fig. 1; and, of course, the shaft 45 and all portions of the carriage 75 which are visible in Figs. 5, 10 and 11 likewise rotate in a clockwise direction in these views. Fig. 5 shows all three of the valve stems 95 which (since they are mounted on the rotary carriage 75) rotate in a clockwise direction in Fig. 5. Now it will be noted that the roller 98 of the valve stem 95 which is furthest to the left in Fig. 5 has just reached the terminus of the broken ring 102 and has just plunged off said ring 102 under the force of its coil spring 99, thus opening its associated valve ports and applying suction to its suction fingers 94. The broken ring 102 is so constructed and positioned that this action (application of suction to fingers 94) takes

place just as the rotating suction fingers 94 arrive over the magazine tubes 15, and preferably just after said fingers 94 have passed the axial centers of the topmost applicator pads 4 in the magazine tubes 15, as shown in Fig. 5.

At this instant the suction in each active suction finger 94, such as that shown in Fig. 7, attracts and elevates the topmost pair of applicator pads 4 and the third or spacer disc 72, and carries them along as the finger 94 continues to rotate; the suction, however, is insufficient to penetrate the relatively impervious spacer 72 and therefore does not disturb the stack of pads immediately below those which have thus been seized by the suction finger. As the suction fingers rotate, the spacer disc 72 on each finger is promptly detached and discarded by additional suction means (hereinafter described) but the suction continues to be applied to the three fingers 94 until the roller 98 of their associated valve stem 95 is again forced back upon the peripheral edge of the broken ring 102. Referring again to Figs. 5 and 10, it will be noted that the cut-away or missing portion of ring 102 extends over only a limited arc and terminates at the precise point where it is desired to cut off the suction and cause the rotating fingers 94 to drop their pairs of pads 4 upon the intermittently moving strips of wrapping material 3. It is at this point that the stationary broken ring 102 resumes, and it will be noted that the uppermost roller 98 in Fig. 5 (that is, the roller 98 of the valve stem 95 nearest the top of Fig. 5) has just been forced back upon the peripheral edge of ring 102 by a resetting device which will now be described.

The resetting device comprises a stationary box 105 which is secured to the stationary collar 100 by screws 106, as shown in Fig. 12. This stationary box is housed within (or covered by) the rotatable hood 82 which forms part of the rotary carriage 75 (Fig. 9) so that the hood 82 continuously rotates around the stationary box 105 during the operation of the machine. Furthermore, the stationary resetter box 105 is fixed to that portion of the collar 100 which supports the forward or leading end 107 of the stationary broken ring 102 (Figs. 5, 10 and 11). It is at this point that the rollers 98 of each continuously rotating valve stem 95 (having previously plunged off the rear or trailing end 108 of broken ring 102 to apply suction to the fingers 94) must be boosted back onto the peripheral edge of the broken ring 102, and this must be accomplished quickly with a snap-action in order to instantly cut off the suction and cause the fingers 94 to deposit their applicator pads on the intermittently moving strips of wrapping material 3.

The resetter box 105 contains a plunger 109 (formed in two parts joined by set screws 111 as shown in Figs. 9 and 12) which is normally urged in an outward direction by a strong coil spring 110, the plunger having a guide pin 112 moving in an elongated slot 113 in box 105 (Figs. 5, 9, 10 and 11). The plunger 109 carries a roller 114 which is adapted to ride on elongated segments 115 or cams 115 secured to the inner cylindrical wall of the rotating hood 82 by set screws 116 for the purpose of forcing said plunger 109 inwardly against the force of its coil spring 110. The cams 115 are three in number; they are equally spaced from each other on the inner cylindrical wall of hood 82; and they are of such length that the blank space between the leading edge of one cam 115 and the trailing edge of the adjacent cam 115 overlies the roller blocks 97 of the respective valve stems 95, as best shown in Fig. 5.

Since the cams 115 rotate continuously with the hood 82 to which they are secured, the leading edge of each cam 115 will periodically strike the roller 114 on the plunger 109 of stationary resetter box 105, thus forcing said plunger 109 inwardly against the tension of its coil spring 110; and the plunger 109 will remain depressed until the trailing edge of that cam 115 arrives opposite the plunger roller 114, whereupon the trailing edge of said cam 115 will ride off the roller 114 and the plunger 109 will plunge outwardly (as it is about to do in Fig. 10) under the tension of its coil spring 110. The plunger 114 will remain in this outward position until the continued rotation of hood 82 brings the leading edge of the next succeeding cam 115 around to the resetter 105, whereupon said cam will engage the plunger roller 114 (Fig. 5) and force the plunger 109 inwardly against the tension of its coil spring 110.

Referring now to Fig. 10, attention is called to the valve stem 95 which is shown at the very top of this figure. The roller 98 on the block 97 of this topmost valve stem 95 is not riding on the peripheral edge of the stationary broken ring 102 because the ring 102 is broken away at this point; hence the said valve stem 95 has its valve ports 96 open (as is the case in Fig. 9) and suction is applied to the suction fingers 94 which are connected to that particular valve stem. However, the said valve stem 95 at the top of Fig. 10 has just reached the edge of the stationary broken ring 102 and it must be instantly forced inwardly against the tension of its coil spring 99 in order to cut off the suction and force of the roller 98 of said valve stem back onto the peripheral edge of ring 102. The way this is accomplished is that at this precise moment (top of Fig. 10) the cam 115, which has been riding over the roller 114 on the plunger 109 of resetter 105, has just rotated to a point where its trailing edge is about to ride off said roller 114, and, at the instant when this happens, the plunger 109 plunges outwardly under the action of its coil spring 110 and strikes against the roller 98 on the block 97 of the said valve stem 95 (at the top of Fig. 10) thus forcing said valve stem upwardly as viewed in Fig. 10 and causing its roller 98 to engage and ride on the peripheral edge of the ring 102.

Fig. 11 shows the parts as they appear at the very instant the above-mentioned resetting operation takes place. The roller block 97 shown in full lines in Fig. 11 has just been forced upwardly (as viewed in Fig. 11) by the plunger 109 of resetting device 105, moving the roller 98 of said block 97 into line with the peripheral edge of the stationary ring 102. Thereupon, as the block 97 continues to rotate (along with the rest of the carriage 75) the roller 98 rolls upon the peripheral edge of the ring 102 as illustrated in dotted lines in Fig. 11. The instant the block 97 is plunged to the position shown in full lines in Fig. 11 the suction in its associated valve 89 (Fig. 9) and suction fingers 94 (Fig. 4) is cut off, and it is at this moment that said file of three fingers 94 arrive in the proper position to drop their pairs of applicator pads 4 on the moving strips 3 of wrapping material shown in Fig. 1.

Referring again to Fig. 11, it will be seen that just after the aforesaid resetting operation takes place a cam 115 rotates into position to engage the roller 114 of the resetter plunger 109 and move said plunger inwardly against the tension of its coil spring 110, in other words to the posi-

tion shown in Fig. 5. All three of the valve stems 95 are actuated in the manner described. The position and dimensions of the stationary broken ring 102 are such that each suction arm 92 and its three depending suction fingers 94 are under suction from the moment they reach the proper position above the magazine tubes 15 to pick up the applicator pads 4 and spacer disc 72 (Figs. 4 and 5) until they arrive at the proper position to deposit said applicator pads 4 on the moving strips of wrapping material 3, and at all other times the suction is turned off. Thus in Fig. 1, the suction arm 92 at the left is under suction since it is in the pick-up position directly over the magazine tubes 15; while the top-most arm 92 in Fig. 1 has just had its suction cut off and it has just deposited its charge of applicator pads 4 on the wrapping strips 3; and the third arm 92 at the lower right of Fig. 1 will not be under suction until its clockwise rotation carries it to the pick-up position above the magazine 6.

Suction nozzles for dislodging spacers

It has been explained how the three suction fingers 94 of each suction arm 92 pass over the tops of the three magazine tubes 15 and, in this specific embodiment of the invention, pick up a stack of two air-permeable applicator pads 4 and a relatively air-impervious spacer 72. Fig. 7 shows a suction finger 94 in the act of lifting two such pads 4 and a spacer 72 off the top of a magazine tube 15, and this represents the actual condition of the three fingers 94 on the suction arm 92 at the left of Fig. 1 overlying the magazine 6. However, before this loaded suction arm 92 (rotating clockwise with the entire rotary carriage 75 in Fig. 1) reaches the "suction-off" position above the strips of wrapping material 3 in Fig. 1 it is necessary to strip off and discard the spacer disc 72 which adheres to the bottom of each pair of applicator pads 4 as shown in Fig. 7. If these spacer discs 72 were not stripped off and discarded, they would be carried along and deposited on the wrapping material 3 along with the applicator pads 4. The mechanisms for dislodging and discarding these spacers 72 are illustrated in Figs. 1, 4, 5, 6, 8 and 13.

The stripping device comprises three tapered suction nozzles 118 connected to a pipe 119 which is mounted on supports 120 constituting part of the framework of the machine and located between the magazine 6 and the table 1 containing the moving wrapping strips 3. The pipe 119 is connected through valve 121 to a suction line 122, as shown in Fig. 13. The valve 121 contains suitable ports (not shown) and a valve stem 123 actuated by a coil spring 124 which urges the stem 123 outwardly (toward the right in Figs. 6 and 13) to close the valve ports and disconnect pipe 119 and nozzles 118 from suction line 122. The inner end of valve stem 123 has a limit head or stop 125 which limits its outward movement, and the outer end of said stem carries a roller 127.

A cam 128 in the general shape of a truncated triangle is secured by screws 129 to a collar 130 which is keyed to the vertical shaft 45 of the machine, as shown in Figs. 4, 6 and 13. This cam 128 rotates continuously with shaft 45 in the horizontal plane of the roller 127 on valve stem 123, and whenever any one of the three truncated peaks of cam 128 strikes the roller 127 it forces the valve stem 123 inwardly (toward the left in Figs. 4, 6 and 13) against the tension of coil spring 124, thus opening valve 121 and connecting pipe

119 and nozzles 118 to the suction line 122. And when any one of the three truncated peaks of cam 128 rides off the roller 127 the coil spring 124 forces the valve stem 123 outwardly (toward the right in Figs. 4, 6 and 13) thereby closing valve 121 and disconnecting pipe 119 and nozzles 118 from suction line 122. The cam 128 has three truncated peaks for applying suction to nozzles 118 for the reason that the rotating carriage 75 has three pick-up arms 92, and one of said truncated peaks actuates valve stem 123 to apply suction to nozzles 118 whenever one of said rotating pick-up arms 92 arrives at the point where its suction fingers 94 (each carrying a pair of applicator pads 4 and an underlying spacer disc 72) sweep over the nozzles 118.

Fig. 8 shows one of the suction fingers 94 in the act of carrying its load of two applicator pads 4 and their underlying spacer 72 over one of the suction nozzles 118, and at such time, of course, air is being drawn upwardly through the finger 94 and downwardly through nozzle 118, as indicated by the arrows in Fig. 8. Since the suction finger 94 holds the pads 4 and spacer 72 near their advancing peripheral edge rather than at their axial center (as previously explained in connection with Fig. 7) the rearward parts of the rather limp pads and spacer will be tilted slightly downwardly as shown in Fig. 8 (and also in Fig. 7) and therefore the pads 4 and spacer 72 will pass partway over the nozzle 118 before the suction in said nozzle (acting directly on the spacer 72) seizes the spacer 72 and sucks it away from the pads 4. As soon as this has been accomplished the suction is cut off from nozzle 118 in the manner previously described, and the spacer 72 will topple off the tapered nozzle 118 and tumble into a suitable waste receptacle (not shown). Of course, the suction still remains on the finger 94 in Fig. 8 which continues to rotate with its stack of two pads 4 (but not the discarded spacer 72) until said finger 94 arrives over one of the moving wrapping strips 3 where the pads 4 are released as previously described.

Referring again to Fig. 8, it will be noted that when the spacer 72 is detached from pads 4 by the suction in nozzle 118, the trailing edge of the advancing pads 4 will usually be tilted slightly downwardly and will usually drag over the toppling spacer 72 and help to shove it over the tapered face of the nozzle 118 as indicated by the dotted position of the tumbling spacer 72 in Fig. 8.

Guard for aligning pads on wrapping strips

It has already been explained how the three suction fingers 94 of each rotating suction arm 92 deposit their stacks of two applicator pads 4 on the respective wrapping strips 3; and Fig. 1 shows said pads 4 neatly arranged in orderly files of equally spaced pads, ready for the final medicating and sealing operations which form no part of the present invention.

However, it may occasionally happen that the three suction fingers 94 on any given arm 92 may not all hold their respective pads 4 in precisely the same position. For example, one of the three fingers 94 on a given arm 92 may hold its pads 4 in the proper off-center position shown in Fig. 8, whereas another of said fingers 94 may possibly grasp its pads 4 at a point somewhat nearer their axial center. In such event the pads 4 would not all be equally spaced on their respectively wrapping strips 3 when dropped

thereon by the simultaneous cutting off of suction in all three fingers 94. In order to avoid such unequal spacing of the pads 4 on the wrapping strips 3, and thereby facilitate the subsequent sealing of the pads in their individual wrappers, we provide the aligning device illustrated in Figs. 1, 5, 17, 18 and 19.

This aligning device comprises a stationary upright plate 132 which extends transversely across and above the table 1 at the station where the suction in fingers 94 is cut off to deposit the pads 4 on the moving wrapping strips 3. The plate 132 is adjustably secured by screws 133 to the standards 2 of the machine, as shown in Figs. 17, 18 and 19. The upright wall of plate 132 is cut away to form three openings 134 through which the moving suction fingers 94 can pass. Individually adjustable flanged gates 135 are secured to the plate 132 adjacent and on opposite sides of the openings 134 by nuts 136 acting in horizontal slots 137 in plate 132. When the moving suction fingers 94 arrive with the pads 4 at the drop-off position, the pads 4 will strike against the respective flanged gates 135, as illustrated in Figs. 17 and 18. Since the suction is cut off simultaneously in all three fingers 94, all three pairs of pads 4 will drop at the same time, and their contact with gates 135 will compel all three pairs of pads to land at the same place on the respective wrapping strips 3 as shown in Fig. 18, even though the momentum of one rotating finger 94 (such as the outermost finger at the top of Fig. 1) may be slightly greater than the momentum of the other fingers.

Furthermore, if one finger 94 should happen to carry its pair of pads 4 slightly in advance of the others, such advance pads will be caught by the gates 135 and retarded for the fraction of a second required to permit the other pads to catch up with it before all the pads are deposited on the wrapping strips 3. The plate 132 and the individual gates 135 are adjusted in advance to insure the proper spacing and alignment of the pads on the wrapping strips.

Operation

The operation of the machine can best be followed by referring to Figs. 1, 4, 14 and 15. First, a freshly filled magazine 6 is secured to the machine by fitting the bottom pins 14b on bottom plate 8 of the magazine into the holes 57 in pivoted bracket 52 at the base of the machine (Fig. 14) and then tilting the top of the magazine inwardly until the pins 14a on top plate 7 enter the slots 58 in bar 59 and are locked therein by releasing the spring-actuated latch 62 (Fig. 15). The elevator platforms 19 supporting the stacks of applicator pads 4 and intervening spacers 72 are at the bottoms of the magazine tubes 15, and the threaded groove 31 in block 26 of the vertically movable cross-bar 23 is in mesh with the vertical threaded shaft 32 on the frame of the machine.

The main drive shaft 49 (Fig. 4) is set in motion and continues to rotate at a uniform rate throughout the operation of the machine. The continuous strips of wrapping material 3 (Fig. 1) are moved intermittently in the direction of the arrows by any suitable means (not shown) at a rate which will depend upon the speed of the rotating carriage 75 and the spacing to be maintained between the pads 4 deposited on said strips 3. The main drive shaft 49 rotates the vertical shaft 45 (Fig. 4) which continuously rotates the carriage 75 as previously explained.

15

The vertical shaft 45 actuates the shaft 40 (Fig. 4) which in turn continuously rotates the vertical threaded shaft 32 (Fig. 14) in a direction to raise the elevator platforms 19 in the magazine tubes 15. It will thus be seen that the elevator platforms 19 continuously raise the applicator pads 4 and spacers 72 in tubes 15 at a uniform rate, while the carriage 75 continuously rotates the suction fingers 94 over the open tops of said tubes 15.

The suction arm 92 in Fig. 4 (which is also shown at the left in Fig. 1) has just arrived with its suction fingers 94 in the pick-up position over the magazine tubes 15. At this moment the valve 89 of that particular suction arm 92 operates (Fig. 9) to connect said fingers 94 to the suction hose 88 (Fig. 4). The air suction in said fingers 94 attracts the two topmost applicator pads 4 and the third or spacer disc 72 of each magazine tube 15, as illustrated in Fig. 7, and the fingers continue to rotate in a clockwise direction in Fig. 1 with these pads and spacer discs in tow.

The advancing fingers thereupon carry their loads over the suction nozzles 118 (Figs. 1 and 5) which at that moment are activated by the mechanism of Fig. 13 to connect said nozzles with the suction line 122. The downward suction in nozzles 118 attracts the relatively impervious spacers 72 (Fig. 8) but cannot penetrate to unseat the pair of applicator pads 4 which are still held by the suction in the rotating fingers 94. Consequently the dislodged spacers 72 topple off the tapered nozzles 118 and are discarded as shown in Fig. 8, while the fingers 94 continue to rotate with the applicator pads 4 unencumbered with the spacers.

When the aforesaid suction arm 92 arrives with its fingers 94 at the discharging position over the intermittently moving wrapping strips 3, its valve 89 operates to disconnect the fingers 94 from the suction hose 88, and the pairs of superposed applicator pads 4 are deposited on the respective wrapping strips 3 with the aid of the aligning device previously described in connection with Figs. 17, 18 and 19. The machine continues to operate in the manner described until the magazine 6 is exhausted, at which time the empty magazine is quickly and easily detached and replaced by a loaded magazine.

Although a specific embodiment has been shown and described herein for purposes of illustration, it will be evident to those skilled in the art that the invention is capable of various other modifications and adaptations within the scope of the appended claims.

The invention claimed is:

1. In the packaging of air-pervious articles such as pharmaceutical applicator pads, the method which comprises arranging such articles in a stack interleaved with relatively impervious spacers, applying suction to the end of said stack to attract and detach the end article and adjacent spacer, moving the detached article and spacer forward while holding same under suction, detaching the spacer from said moving article, and then removing the suction from said article to release same.

2. In the packaging of air-pervious articles such as pharmaceutical applicator pads, the method which comprises arranging such articles in a stock interleaved with relatively impervious spacers, applying suction to the end of said stack to attract and detach the end article and adjacent spacer, moving the detached article and

16

spacer forward while holding same under suction, applying a counter-suction to said moving spacer sufficient to detach same from said moving article, and then removing the suction from said article to release same.

3. In the packaging of air-pervious articles such as pharmaceutical applicator pads, the method which comprises arranging such articles in a stack containing groups of superposed articles separated by relatively impervious spacers, applying suction to the end of said stack to attract and detach the end group of articles and the adjacent spacer, moving the detached group and spacer forward while holding same under suction, detaching the spacer from said moving group of articles, and then removing the suction from said group to release same.

4. In the packaging of air-pervious articles such as pharmaceutical applicator pads, the method which comprises arranging such articles in a stack containing groups of superposed articles separated from succeeding groups by individual relatively impervious spacers, applying suction to the end of said stack to attract and detach the end group of articles and the adjacent spacer, moving the detached group and spacer forward while holding same under suction, applying a counter-suction to said moving spacer sufficient to detach same from said moving group of articles, and then removing the suction from said group to release same.

5. In the packaging of air-pervious articles such as pharmaceutical applicator pads, the method which comprises arranging such articles in an upright stack interleaved with relatively impervious spacers, elevating said stack of articles and spacers, periodically applying suction to the top of said stack to attract and detach the topmost article and its underlying spacer, moving the detached article and spacer forward while holding same under suction, detaching the spacer from said moving article, and then removing the suction from said article to release same.

6. In the packaging of air-pervious articles such as pharmaceutical applicator pads, the method which comprises arranging such articles in an upright stack interleaved with relatively impervious spacers, elevating said stack of articles and spacers, periodically applying suction to the top of said rising stack to attract and detach the topmost article and its underlying spacer, moving the detached article and spacer forward while holding same under suction, applying a counter-suction to the bottom of said moving spacer sufficient to detach same from said moving article, and then removing the suction from said article to release same.

7. In the packaging of air-pervious articles such as pharmaceutical applicator pads, the method which comprises arranging such articles in an upright stack containing groups of superposed articles separated from underlying groups by individual relatively impervious spacers, continuously elevating said stack, periodically applying suction to the top of said stack to attract and detach the topmost group of articles and the underlying spacer, moving the detached group and spacer forward while holding same under suction, detaching the spacer from said moving group of articles, and then removing the suction from said group to release same.

8. In the packaging of air-pervious articles such as pharmaceutical applicator pads, the method which comprises arranging such articles in an upright stack containing groups of super-

posed articles separated from underlying groups by individual relatively impervious spacers, continuously elevating said stack, periodically applying suction to the top of said stack to attract and detach the topmost group of articles and the underlying spacer, moving the detached group and spacer forward while holding same under suction, applying a counter-suction to the bottom of said moving spacer sufficient to detach same from said moving group of articles, and then removing the suction from said group of articles to release same.

9. In the packaging of air-pervious articles such as pharmaceutical applicator pads, the method which comprises arranging such articles in a stack interleaved with relatively impervious spacers, applying suction to the end of said stack to attract and detach the end article and adjacent spacer, moving the detached article and spacer forward while holding same under suction, detaching the spacer from said moving article, moving a strip of wrapping material beneath the path of movement of said article, and removing the suction from said article when over said wrapping strip to deposit said article on said strip.

10. In the packaging of air-pervious articles such as pharmaceutical applicator pads, the method which comprises arranging such articles in an upright stack interleaved with relatively impervious spacers, elevating said stack of articles and spacers, periodically applying suction to the top of said rising stack to attract and detach the topmost article and the underlying spacer, moving the detached article and spacer forward while holding same under suction, applying a counter-suction to the bottom of said moving spacer sufficient to detach same from said moving article, moving a strip of wrapping material beneath the path of movement of said article, and removing the suction from said article when over said wrapping strip to deposit said article on said strip.

11. In the packaging of air-pervious articles such as pharmaceutical applicator pads, the method which comprises arranging such articles in a plurality of aligned upright stacks interleaved with relatively impervious spacers, elevating said stacks of articles and spacers, periodically applying suction simultaneously to the tops of said rising stacks to attract and detach each topmost article and its underlying spacer, moving the detached articles and underlying spacers forward in spaced relation while holding same under suction, applying counter-suction to the bottom of each moving spacer sufficient to detach same from said moving articles, moving strips of wrapping material beneath the respective paths of movement of said articles, retarding the moving articles when over said wrapping strips to align them above the respective strips, and simultaneously removing the suction from the aligned articles to deposit them on said strips.

12. In the packaging of air-pervious articles such as pharmaceutical applicator pads, the method which comprises arranging such articles in a plurality of aligned upright stacks each containing groups of superposed articles separated from underlying groups by individual relatively impervious spacers, continuously elevating said stacks of articles and spacers, periodically applying suction simultaneously to the tops of said rising stacks to attract and detach the topmost groups of articles and their individual underlying spacers, moving the detached groups and

spacers forward in spaced relation while holding same under tension, applying counter-suction to the bottom of each moving spacer sufficient to detach same from said moving groups of articles, 5 moving strips of wrapping material beneath the paths of movement of the respective groups of articles, retarding the movement of said groups of articles when over said wrapping strips to align them above the respective strips, and simultaneously removing the suction from the aligned groups of articles to deposit them on said strips.

13. In a machine for packaging air-pervious articles, a magazine adapted to contain a succession of such articles and intervening relatively impervious spacers, a movable suction member adapted to move in proximity to said magazine to attract and remove the outermost articles and spacer, means for removing said spacer from said suction member, and means independent of said 15 last-mentioned means for removing said articles from said suction member.

14. In a machine for packaging air-pervious articles, a magazine adapted to contain a stack of such articles and intervening relatively impervious spacers, a movable carriage having a plurality of suction members positioned to pass successively over said magazine, a source of suction connected to said carriage, means for connecting said suction source to each suction member over said magazine to attract and remove the outermost articles and adjacent spacer, means for removing said spacers from said suction members, and means independent of said last-mentioned means for cutting off the suction in said 20 suction members to release said articles.

15. In a machine for packaging air-pervious articles, a magazine adapted to contain a stack of such articles and intervening relatively impervious spacers, a movable carriage having a plurality of suction members positioned to pass successively over said magazine, a source of suction connected to said carriage, means controlled by the carriage in its movement to connect said suction source to each suction member over said 25 magazine to attract and remove the outermost articles and adjacent spacer, means for supporting a wrapping material beneath said suction members beyond said magazine, means between said magazine and said wrapping material for separating said spacers from the air-pervious articles held by said suction members, and means controlled by the movement of said carriage to cut off the suction of each suction member overlying said wrapping material to release said articles.

16. In a machine for packaging air-pervious articles, a magazine adapted to contain a stack of such articles and intervening relatively impervious spacers, means for advancing said stack in said magazine, a movable carriage having a plurality of suction members positioned to pass successively over said magazine, a source of suction connected to said carriage, a plurality of valves on said carriage individual to the respective suction members, means controlled by the carriage in its movement to open said valves and connect said suction source to each suction member over said magazine to attract and remove the outermost articles and adjacent spacer, means for supporting a wrapping material beneath said suction members beyond said magazine, means between said magazine and said wrapping material for separating said spacers from the air-pervious articles held by said suction members, and means controlled by the carriage in its move- 30 35 40 45 50 55 60 65 70

ment to close the valve and cut off the suction of each suction member overlying said wrapping material to release said articles.

17. In a machine for packaging air-pervious articles, a magazine adapted to contain a stack of such articles and intervening relatively impervious spacers, means for advancing said stack in said magazine, a movable carriage having a plurality of suction members positioned to pass successively over said magazine, a source of suction connected to said carriage, a plurality of valves on said carriage individual to the respective suction members, means controlled by the carriage in its movement to open said valves and connect said suction source to each suction member over said magazine to attract and remove the outermost articles and adjacent spacer, means for supporting a wrapping material beneath said suction members beyond said magazine, additional suction means between said magazine and said wrapping material beneath the path of movement of said suction members to attract and remove said spacers, and means controlled by the carriage in its movement to close the valve and cut off the suction of each suction member overlying said wrapping material to release said articles.

18. In a machine for packaging air-pervious articles, a magazine adapted to contain a vertical stack of such articles and intervening relatively impervious spacers, means for elevating said stack in said magazine, a rotatable carriage having a plurality of suction members positioned to pass successively over said magazine, a source of suction connected to said carriage, a plurality of valves on said carriage individual to the respective suction members, means controlled by the carriage in its rotation to open said valves and connect said suction source to each suction member over said magazine to attract and remove the topmost articles and underlying spacer, means for supporting a wrapping material beneath said suction members beyond said magazine, means between said magazine and said wrapping material for separating said spacers from the air-pervious articles held by said suction members, and means controlled by the carriage in its rotation to close the valve and cut off the suction of each suction member overlying said wrapping material to release said articles.

19. In a machine for packaging air-pervious articles, a magazine adapted to contain a vertical stack of such articles and intervening relatively impervious spacers, means for continuously elevating said stack in said magazine, a rotatable carriage having a plurality of suction members positioned to pass successively over said magazine, a source of suction connected to said carriage, a plurality of valves on said carriage individual to the respective suction members, means controlled by the carriage in its rotation to open said valves and connect said suction source to each suction member over said magazine to attract and remove the topmost articles and underlying spacer, means for supporting a wrapping material beneath said suction members beyond said magazine, additional suction means between said magazine and said wrapping material beneath the path of movement of said suction members to attract and remove said spacers, and means controlled by the carriage in its rotation to close the valve and cut off the suction of each suction member overlying said wrapping material to release said articles.

20. In a machine for packaging air-pervious

articles such as pharmaceutical applicator pads, a magazine adapted to contain a vertical stack of pads and intervening relatively impervious spacers, means for continuously elevating said stack in said magazine, a continuously rotatable carriage having a plurality of suction members positioned to pass successively over said magazine, a source of suction connected to said carriage, a plurality of valves on said carriage individual to the respective suction members, means cooperating with said valves and controlled by the carriage in its rotation to open said valves and connect said suction source to each suction member over said magazine to attract and remove the topmost pads and underlying spacer, means for supporting a wrapping material beneath said suction members beyond said magazine, additional suction means between said magazine and said wrapping material beneath the path of movement of said suction members to attract and remove said spacers, and means controlled by the carriage in its rotation to close the valve and cut off the suction of each suction member overlying said wrapping material to release said pads.

21. In a machine for packaging air-pervious articles such as pharmaceutical applicator pads, a magazine adapted to contain a vertical stack of pads and intervening relatively impervious spacers, means for continuously elevating said stack in said magazine, a continuously rotatable carriage having a plurality of suction members positioned to pass successively over said magazine, a source of suction connected to said carriage, a plurality of valves on said carriage individual to the respective suction members, means cooperating with said valves and controlled by the carriage in its rotation to open said valves and connect said suction source to each suction member over said magazine to attract and remove the topmost pads and underlying spacer, means for supporting a wrapping material beneath said suction members beyond said magazine, additional suction means between said magazine and said wrapping material beneath the path of movement of said suction members to attract and remove said spacers, and means controlled by the carriage in its rotation to close the valve and cut off the suction of each suction member overlying said wrapping material to release the pads carried by said member, and means adjacent said wrapping material engageable with said pads to position said pads on said wrapping material.

22. In a machine for packaging porous articles such as pharmaceutical applicator pads, a magazine including a plurality of vertical supply compartments adapted to contain stacks of such pads and intervening relatively non-porous spacers, a rotatable carriage having a plurality of suction arms movable over said magazine, a plurality of suction fingers on each of said arms positioned to pass over the respective supply compartments to exert suction thereon, a source of suction connected to said carriage, means controlled by the carriage in its rotation to connect said source of suction to the respective arms and fingers passing said magazine to attract and remove the topmost pads and underlying spacers, means for supporting a plurality of strips of wrapping material beneath the path of movement of the respective fingers, means between said magazine and said wrapping strips for separating the spacers from the pads carried by said fingers and discarding the spacers.

ers, and means controlled by the carriage in its rotation to cut off the suction to each suction arm and finger overlying said wrapping strips to release the pads carried by said fingers.

23. In a machine for packaging porous articles such as pharmaceutical applicator pads, a magazine including a plurality of vertical supply compartments adapted to contain stacks of such pads and intervening relatively non-porous spacers, means for elevating the contents of said compartments, a rotatable carriage having a plurality of suction arms movable over said magazine, a plurality of suction fingers on each of said arms positioned to pass over the respective supply compartments to exert suction thereon, a source of suction connected to said carriage, a plurality of valves on said carriage individual to the respective suction arms for separately connecting said arms to said source of suction, means controlled by the carriage in its rotation to open said valves and apply suction through the respective arms and fingers passing said magazine to attract and remove the topmost pads and underlying spacers, means for supporting a plurality of strips of wrapping material beneath the path of movement of the respective fingers, means between said magazine and said wrapping strips for removing and discarding the spacers carried by said fingers, and means controlled by the carriage in its rotation to close the valve and cut off the suction of each suction arm and finger overlying said wrapping strips to release the pads carried by said fingers.

24. In a machine for packaging porous articles such as pharmaceutical applicator pads, a magazine including a plurality of vertical supply compartments adapted to contain stacks of such pads and intervening relatively non-porous spacers, means for elevating the contents of said compartments, a rotatable carriage having a plurality of suction arms movable over said magazine, a plurality of suction fingers on each of said arms positioned to pass over the respective supply compartments to exert suction thereon, a source of suction connected to said carriage, a plurality of valves on said carriage individual to the respective suction arms for separately connecting said arms to said source of suction, means controlled by the carriage in its rotation to open said valves and apply suction through the respective arms and fingers passing said magazine to attract and remove the topmost pads and underlying spacers, means for supporting a plurality of strips of wrapping material beneath the path of movement of the respective fingers, a plurality of suction nozzles between said magazine and said wrapping strips beneath the path of movement of said fingers, means coordinated with the rotation of said carriage to apply suction through said nozzles upon the passage of said fingers to attract and discard the spacers carried beneath said fingers, and means controlled by the carriage in its rotation to close the valve and cut off the suction of each suction arm and finger overlying said wrapping strips to release the pads carried by said fingers.

25. In a machine for packaging porous articles such as pharmaceutical applicator pads, a magazine including a plurality of vertical supply compartments open at the top and adapted to contain stacks of such pads arranged in groups with intervening relatively non-porous spacers, elevator platforms in said compartments for

supporting said stacks therein, means for elevating said platforms to simultaneously raise the contents of said compartments, a rotatable carriage having a plurality of suction arms movable over said magazine, a plurality of suction fingers on each of said arms positioned to pass over the open tops of the respective supply compartments to exert suction thereon, a source of suction connected to said carriage, a plurality of valves on said carriage individual to the respective suction arms for separately connecting said arms to said source of suction, means cooperating with said valves and controlled by the carriage in its rotation to open said valves and apply suction through the respective suction arms and fingers passing said magazine to attract and remove the topmost pads and the underlying spacers subjected to suction, means for supporting a plurality of strips of wrapping material beneath the path of movement of the respective suction fingers, a plurality of suction nozzles between said magazine and said wrapping strips beneath the path of movement of said suction fingers, means coordinated with the rotation of said carriage to apply downward suction through said nozzles upon the passage of said suction fingers to attract and discard the spacers carried beneath said fingers, and means controlled by the carriage in its rotation to close the valve and cut off the suction of each suction arm and finger overlying said wrapping strips to release the pads carried by said fingers.

26. In a machine for packaging porous articles such as pharmaceutical applicator pads, a magazine including a plurality of vertical supply compartments open at the top and adapted to contain stacks of such pads arranged in groups with intervening relatively non-porous spacers, elevator platforms in said compartments for supporting said stacks therein, means for continuously elevating said platforms to simultaneously raise the contents of said compartments, a continuously rotatable carriage having a plurality of equally spaced suction arms movable over said magazine, a plurality of suction fingers on each of said arms positioned to pass directly over the open tops of the respective supply compartments at a height to exert suction thereon, a source of suction connected to said carriage, a plurality of valves on said carriage individual to the respective suction arms for separately connecting said arms to said source of suction, means cooperating with said valves and controlled by the carriage in its rotation to open said valves and apply suction through the respective suction arms and fingers passing said magazine to attract and remove the topmost pads and the underlying spacers subjected to suction, means for supporting a plurality of horizontal strips of wrapping material beneath the path of movement of the respective suction fingers, a plurality of tapered suction nozzles between said magazine and said wrapping strips directly beneath the path of movement of said suction fingers, means coordinated with the rotation of said carriage to momentarily apply downward suction through said nozzles upon the passage of said suction fingers to attract and discard the spacers carried beneath said fingers, and means controlled by the carriage in its rotation to close the valve and cut off the suction of each suction arm and finger overlying said wrapping strips to release the pads carried by said fingers.

27. In a machine for packaging porous articles such as pharmaceutical applicator pads, a maga-

zine including a plurality of vertical supply compartments open at the top and adapted to contain stacks of such pads arranged in groups with intervening relatively non-porous spacers, elevator platforms in said compartments for supporting said stacks therein, means for continuously elevating said platforms to simultaneously raise the contents of said compartments, a continuously rotatable carriage having a plurality of equally spaced suction arms movable over said magazine, a plurality of suction fingers on each of said arms positioned to pass directly over the open tops of the respective supply compartments at a height to exert suction thereon, a source of suction connected to said carriage, a plurality of valves on said carriage individual to the respective suction arms for separately connecting said arms to said source of suction, means cooperating with said valves and controlled by the carriage in its rotation to open said valves and apply suction through the respective suction arms and fingers passing said magazine to attract and remove the topmost pads and the underlying spacers subjected to suction, means for supporting a plurality of horizontal strips of wrapping material beneath the path of movement of the respective suction fingers, a plurality of tapered suction nozzles between said magazine and said wrapping strips directly beneath the path of movement of said suction fingers, means coordinated with the rotation of said carriage to momentarily apply downward suction through said nozzles upon the passage of said suction fingers to attract and discard the spacers carried beneath said fingers, means controlled by the carriage in its rotation to close the valve and cut off the suction of each suction arm and finger overlying said wrapping strips to release the pads carried by said fingers, and means cooperating with said strips of wrapping material and engageable with the pads carried by said fingers for positioning said pads on said wrapping strips.

28. In a machine for packaging porous articles such as pharmaceutical applicator pads, a magazine including a plurality of vertical supply compartments open at the top and adapted to contain stacks of such pads arranged in groups with intervening relatively non-porous spacers, elevator platforms in said compartments for supporting said stacks therein, means for continuously elevating said platforms to simultaneously

raise the contents of said compartments, flexible means partly overlying the tops of said compartments to lightly engage and compress the rising stacks and tilt the topmost layers therein, a continuously rotatable carriage having a plurality of equally spaced suction arms movable over said magazine, a plurality of suction fingers on each of said arms positioned to pass directly over the open tops of the respective supply compartments at a height to exert suction thereon, a source of suction connected to said carriage, a plurality of valves on said carriage individual to the respective suction arms for separately connecting said arms to said source of suction, means cooperating with said valves and controlled by the carriage in its rotation to open said valves and apply suction through the respective suction arms and fingers passing said magazine to attract and remove the topmost pads and the underlying spacers subjected to suction, means for supporting a plurality of horizontal strips of wrapping material beneath the path of movement of the respective suction fingers, a plurality of tapered suction nozzles between said magazine and said wrapping strips directly beneath the path of movement of said suction fingers, means coordinated with the rotation of said carriage to momentarily apply downward suction through said nozzles upon the passage of said suction fingers to attract and discard the spacers carried beneath said fingers, means controlled by the carriage in its rotation to close the valve and cut off the suction of each suction arm and finger overlying said wrapping strips to release the pads carried by said fingers, and means cooperating with said strips of wrapping material and engageable with the pads carried by said fingers for positioning said pads on said wrapping strips.

LEONARD A. HERZIG.
MARTIN COAN.
